UNITED STATES PATENT OFFICE.

CAVETT V. V. TURNER, OF HELENA, ARKANSAS.

RAIL-JOINT.

1,019,203.

Specification of Letters Patent. Patented Mar. 5, 1912.

Application filed December 8, 1911. Serial No. 664,548.

To all whom it may concern:

Be it known that I, CAVETT V. V. TURNER, a citizen of the United States, residing at Helena, in the county of Phillips and State of Arkansas, have invented new and useful Improvements in Rail-Joints, of which the following is a specification.

This invention relates to improvements in rail joints.

10 In carrying out my invention it is my purpose to provide a simple and effective device which may be easily and quickly applied to the meeting ends of a pair of rails, and which will effectively support the said 15 rails at their juncture to prevent the lateral as well as the sagging movement thereof and to sustain the said rails as strong and efficient at their joint as at the body of either of the said rails, thereby producing a substantially continuous rail.

20 In the drawings, Figure 1 is a side elevation of a pair of rails constructed in accordance with the present invention. Fig. 2 is a vertical transverse sectional view taken 25 upon the line 2—2 of Fig. 1. Fig. 3 is a similar sectional view taken upon the line 3—3 of Fig. 1. Fig. 4 is a horizontal sectional view. Fig. 5 is a view of one of the 30 rail ends. Fig. 6 is a similar view of the rail connecting member or chair. Fig. 7 is a cross sectional view of a modified form of the chair.

35 Referring now to the drawings in detail, the numerals 1 and 2 designate a pair of ordinary rail-way rails. These rails adjacent their ends have their base flanges and a portion of the webs cut away to provide the head and web extensions, the same being indicated by the numeral 3. The cut in portion 40 of the web is approximately central of the height of the rails and provides a longitudinally extending horizontally straight wall 4 and a vertical wall 5, the said vertical wall extending through the base flange 45 of the rail.

Both of the rails, it is to be understood are of a similar formation at their ends, and in order to fill the space provided by the said cut away portions as well as to effectively 50 support the rails at their meeting ends, I provide a pair of fish plates 6, the same being of the usual angular formation comprising a vertical wall 7 and an angular wall 8 which is integrally connected to the 55 vertical wall. Each of the fish plates 6 is centrally provided with what I term a bear-

ing block 9. This bearing block is of a length equaling the space provided by the cut away portions of the rail ends, and is of a width approximately equaling one half 60 of the height of the webs. The bearing blocks 9 of the web sections may be integrally formed with the said sections or may be welded thereon and each of the said blocks comprises a flange 10 which extends 65 below the flange 8 of each of the fish plates. The base flanges 8, are, of course, of a width approximately equaling the distance between the web and the outer edge of the base flange of one of the faces of the rails, 70 and the base flanges are each provided with a longitudinally extending depending portion 11 and the same is adapted to contact with the longitudinal edges of the rails. The flange 10 of the blocks 9 terminates at 75 the inner face of the depending portion 11, so that the blocks 9 together with their flanges 10 engage the space provided by the cut away portions of the rails, and the said flanges contact with the flanges of the rails 80 provided by the vertical walls 5, when the fish plates are fastened upon the rails. The vertical members 7 of the fish plates are provided with spaced openings 12 and 13, and the said openings are adapted to register with elongated openings 14 and 15 provided by each of the rail ends and their extensions and these alining openings are adapted for the reception of securing elements such as the usual bolts 16 and nuts 17. The angular flange of each of the fish plates is provided with suitable openings 18, the latter being arranged directly adjacent the longitudinal edges of the base flanges of the rails, and are adapted to receive spikes 19, whereby the rails and fish plates are effectively secured upon the ties of the road bed.

In Fig. 7 I have illustrated a bearing block 20 which is integrally formed with oppositely extending base flanges 21, while welded to the block as well as to its base flange are the oppositely arranged angular fish plates 22 and 23. The vertical members of the fish plates project a suitable distance 1 above the upper edge of the block 20 and are provided with registering openings 24 for the reception of securing elements, similar to the members 16 and 17.

From the above description, it will be understood that the bearing block and the fish plates provide a chair for the ends of

the rails, the said bearing block and fish plates being preferably welded together, and of course it is obvious that the said members may be constructed of separate elements or the said members may be formed from a single casting. The bearing block however, is preferably constructed of some hardened material such as Harveyized steel, while for the sake of economy the fish plates may be constructed of some efficient but less expensive material such as cast steel or the like.

Having thus described the invention what I claim is:—

15. 1. In a device for the purpose set forth the combination with a pair of rail-way rails, said rails having the upper portion of their webs and their heads extending beyond the main body of each of the rails, a bearing block comprising a flanged member having a central web or extension arranged to support the extended portions of the said rails, angular fish plates secured to the bearing block, the said fish plates 20 having their ends formed of some resilient material and projecting beyond the ends of the bearing block, and means for securing the fish plates to the webs and the web extensions of the rails.
- 25.

2. In combination with the meeting ends 30 of a pair of rail-way rails, each of said rails having a portion of its web and its head extending beyond the rail proper, a chair for the rail ends, said chair embodying a central bearing block of hardened metal and having 35 angular fish plates secured thereto, the bearing block being centrally provided with an upstanding portion forming a web which is adapted to engage the lower walls of the web extensions of the rails, the said bearing 40 block being of a length equaling that of the extended portions of the rails, the fish plates of the chair extending beyond the ends of the bearing block, the said extending portions being formed of resilient material and 45 adapted to tightly compress against the base flanges and webs of the rails when the chair is positioned upon the rails, means for securing the vertical members of the fish plates to the webs and to the extensions of 50 the webs, and means for securing the chair to the ties of the rails.

In testimony whereof I affix my signature in presence of two witnesses.

CAVETT V. V. TURNER.
